UNITED STATES PATENT OFFICE

WILLIAM J. HAGMAN, OF PHILADELPHIA, PENNSYLVANIA

FORGE HAMMER

Application filed February 11, 1925. Serial No. 8,461.

My invention relates to hammers and it has particular relation to cushioning apparatus therefor.

Inasmuch as the usual forge hammer has a vertically reciprocal piston rod with a variable stroke, the length of which stroke is subject to the control of the operator, it often happens that through carelessness or poor judgment on the part of said operator, the piston is driven against the cylinder head, thus causing it to shatter and the fragments to be projected in the air.

Moreover, piston rods have been known to break loose from the rams or cross-heads, or the rods to snap apart at some point in their length. Should either of these accidents occur while pressure is applied to the underside of the piston, a quick upward drive of the piston results and the cylinder head is shattered. Under some conditions, even the piston itself may be thrown from the hammer.

The danger accompanying such accidents is manifest, and, in a measure, has been guarded against by various kinds of buffers but these buffers have been of the resilient type and are effective only under relatively light loads.

Another method of guarding against such accidents involves the pressing or cushioning of the gases above the piston, but to obtain a suitable cushion within the hammer cylinder in the ordinary manner would necessitate a considerable extension of the cylinder above the upper steam port in order to provide for a reasonable travel of the piston after it has closed said port. Such addition to the cylinder, however, would be wasteful of the steam or compressed air or other actuating fluid medium.

An object of my invention, therefore, is to provide a suitable cushioning device that shall avoid the above-noted disadvantages and yet be simple in design and efficient and reliable in operation. To this end, I provide a mechanical choke to the exhaust gases which automatically comes into an effective position when needed and which is movable into an ineffective position out of the path

of travel of the piston when it is not required and conditions are normal.

With these and other objects and applications in mind, my invention further consists in the details of construction and operation and arrangement, hereinafter described and claimed and illustrated in the accompanying drawing, wherein

Fig. 1 is a side elevational view partially in section of a forge hammer embodying my invention; and

Fig. 2 is an enlarged detail sectional view of the cushioning apparatus shown in Fig. 1.

In the illustrated embodiment of my invention shown in the drawing, a forge hammer 1 comprises a frame 2 which provides ways 3 and 4 for a vertically movable hammer 5, a lower end of which carries a die 6 adapted to co-act with a second die 7 carried on a die block 8 which rests on an anvil 9.

An upper end of the hammer 1 is secured to a piston-rod 11. The latter is secured to a lower face 12 of a main piston 13 which is vertically movable in a main hammer cylinder 14 supported in the upper portion of the frame 2.

A lower end 15 of the main cylinder 14 is provided with a lower port 16 which communicates by means of a passage 17 with one port 18 of a valve chest 19. A second port 21 of the valve chest 19 communicates by means of a passage 22 with an upper end 23 of the main cylinder 14, as will appear more fully hereafter. An intermediate port 24 communicates with a pressure fluid inlet opening 25. The pressure fluid may, for example, be steam or compressed air or other motive fluid.

The valve chest 19 may be designed to receive a piston valve 26 of usual construction, and it may be operated by means of a valve rod 27 which extends from the valve chest 19. The piston valve 26 may comprise a tubular element 28, opposite ends of which are respectively adapted to close the ports 18 and 21 when in the mid-position shown in Fig. 1. The central portion of the tubular element 28 is of smaller diameter than the end portions which cooperate with the ports 18 and 21, whereby a passage may be

100

provided from the intermediate port 24 to either of the ports 18 or 21, depending upon the position of the tubular element 28.

When the tubular element 28 is moved downwardly from the position shown in Fig. 1 so as to uncover the port 21, the passage 22, that extends to the upper end of cylinder 23, is directly connected through the tubular element 28 to an exhaust passage 29 which extends from a lower portion of the valve chest 19 below the port 18. When the tubular element 28 is moved upwardly from the position shown in Fig. 1, the port 18 is uncovered, thus connecting the lower end portion of the main cylinder 14 to the valve chest exhaust passage 29, as will be readily apparent to those skilled in the art.

As above-noted, my invention contemplates a mechanical choke 30, which shall be operable to trap the exhaust fluid or gases in the upper end 23 of the main cylinder 14 should the operator permit the piston 13 to move upwardly in the main cylinder 14 beyond a predetermined extent, thus causing the piston 13 to be quickly brought to rest without a violent shock or the breaking of related parts. In the drawings, I have shown one form of mechanical choke 30 for accomplishing the afore-mentioned desired results and it comprises a vertically extending casing or cylinder 31, a lower end 32 of which is formed to constitute the upper head of the main cylinder 14 and is secured thereto by bolts 33 and 34.

A tubular plunger 35 is mounted for vertical movement in a perforation 36 in the lower end 32 of the auxiliary cylinder 31, and it has a lower open end 37, constituting the upper port of the main cylinder 14. The port 37 is adapted to be closed by the upper side 38 of the main piston 13 when the latter moves upward at a dangerous speed beyond a predetermined point, that is, beyond a point where the application of fluid pressure to the upper side 38 of the main piston 13 will check the upward movement of the same before it strikes the piston head, all as will appear hereinafter.

The upper end of the tubular plunger 35 is closed by means of a plug 41 which is secured in threaded engagement therewith, as illustrated. The free end of the plug 41 is formed to constitute a piston 42. In order that the extent of movement of the tubular plunger 35 into the upper end portion 23 of the main cylinder 14 may be normally limited to that shown in Fig. 1, an inwardly extending annular flange 43 is formed on the inner side of the auxiliary cylinder 31, said flange constituting a stop for the lower edge of the auxiliary piston 42.

The auxiliary cylinder 31 is thus divided by the auxiliary piston 42 into upper and lower portions 44 and 45 having ports 46 and 47, respectively. The upper port 46

is connected by means of a pipe 48 with a port 49 in the lower end portion 15 of the main cylinder 14, whereby motive fluid may be substantially simultaneously supplied to the lower side of the main piston 13 and to the upper side of the auxiliary piston 42, thus causing a movement of the tubular plunger 35 into the main cylinder 14 substantially simultaneously with the upward movement of the main piston 13. The motive fluid on the upper side of the auxiliary piston 42 also provides a cushioning effect to the vertical movement of the piston 42 and the plunger 35 due to the main piston 13 striking said plunger 35.

A plurality of orifices 50 are formed in the upper end of the tubular plunger 35, whereby the port 47, which is positioned in the lower end portion 45 of the auxiliary cylinder 31 may be continuously in communication with the open end 37 of the tubular plunger 35. The passage 22 leading from the port 21 of the valve chest 19 to the lower port 47 is thus in continuous communication with adjacent sides of the main and auxiliary pistons 13 and 42, respectively.

When the operator desires to raise the die 6 out of engagement with the disc 7, the tubular element 28 is moved downwardly from the position shown in Fig. 1 so as to interconnect the ports 24 and 18. Fluid pressure is now supplied to the underside 12 of the piston 13, causing an upward movement of the same. In the prior art machines as above-noted, this movement may be checked by further actuating the tubular element 28 so as to cause a supply of fluid pressure to the upper side of the piston 13, while simultaneously exhausting the fluid pressure from the underside thereof. The inherent disadvantages of this method of control are readily apparent to those skilled in the art.

In accordance with my invention, as hereinabove noted, fluid pressure is supplied through passage 48 to the upper side of the auxiliary piston 42 simultaneously with the application of the fluid pressure to the lower side of the piston 13, with the result that the piston 42 is actuated downwardly into engagement with the annular flange 43, as shown in Figure 1, while the piston 13 is actuated upwardly.

When the operator desires to reverse the movement of the piston 13, the tubular element 28 is actuated upwardly so as to uncover the discharge port 18, and hence permit the motive fluid to exhaust from the underside of the piston 13 through the outlet passage 29. The upward movement of the tubular element 28 just noted also serves to connect the fluid supply opening 25 to the port 47, with the result that fluid pressure is supplied to the upper side of the main piston 13 and to the lower side of the auxili-

ary piston 42, causing an upward movement of the latter and a downward movement of the former. The withdrawal of the lower end portion of the tubular plunger 35 from the path of travel of the upwardly moving piston 13 is an important feature of my invention, inasmuch as it prevents an unnecessary striking of the tubular plunger 35 by the main piston 13. The movement of the piston 13 being now reversed, the die 6 is moved downwardly to accomplish the work desired.

Should the operator maintain the fluid pressure on the underside 12 of the main piston 13 so long that the subsequent application of the fluid pressure to the upper side thereof is not sufficient to prevent the piston 13 from striking the upper end of the main cylinder 14, or what is equivalent thereto, 20 should the piston 13 become detached from the ram 5, the open end 37 of the safety plunger 35 is closed by the adjacent face 38 of the piston 13, trapping the exhaust fluid in the upper end of the main cylinder 14. As 25 the piston 13 continues to move upwardly, the gases are compressed, forming an elastic cushion which very quickly brings the piston 13 to rest without a violent shock. The vertical movement of the tubular plunger 35 is 30 further resisted by the force of the fluid pressure acting on the upper side of the auxiliary piston 42. When it is desired again to cause a downward movement of the piston 13, the tubular element 28 is moved upwardly from 35 the position of Fig. 1 so as to permit a supply of the pressure fluid to the adjacent sides of the pistons 13 and 43, respectively.

While I have shown only one form of embodiment of my invention, for the purpose of describing the same and illustrating its principles of construction and operation, it is apparent that various changes and modifications may be made therein without departing from the spirit of my invention, and 45 I desire, therefore, that only such limitations shall be imposed thereon as are indicated in the appended claims or as are demanded by the prior art.

I claim:

50 1. In a hammer having a main cylinder provided with a main piston, a passage for conveying fluid to and from the upper end of said main cylinder, and means for controlling the flow of fluid to and from said fluid passage; the combination therewith of a plunger reciprocally mounted at and extending into the upper end of said main cylinder, said plunger being hollow and open at its end nearest said main piston and having 55 a duct affording communication between said opening and said fluid passage, said plunger being adapted to have its open end engaged and the opening therein closed by said main piston, thereby preventing the exhaust of 60 fluid from the upper end of said main cylinder,

inder, for effecting a compression of fluid remaining in the said upper end of said main cylinder, when said main piston approaches the said upper end of said main cylinder beyond a predetermined point in its travel 70 within said main cylinder, the fluid from the upper end of said main cylinder normally exhausting through the opening and duct in the plunger to the said fluid passage when the fluid controlling means is operated to permit the exhaust of fluid from said fluid passage; said plunger being operated out of the path of travel of said main piston when said fluid controlling means is operated to admit fluid to said fluid passage and through said duct and said plunger opening into the upper end of said main cylinder, said operation of said plunger being effected by the force of the fluid exerted between the main piston and the plunger.

2. In a hammer having a main cylinder provided with a main piston, passages for conveying fluid to and from the opposite ends of said main cylinder, and means for controlling the flow of fluid to and from said passages, the combination therewith of an auxiliary cylinder having an auxiliary piston provided with a hollow plunger extending into the upper end of said main cylinder and adapted to be engaged by said main piston as the same approaches the upper end of said main cylinder, said hollow plunger being open at its end toward said piston and having openings communicating with the fluid passage for the upper end of said main cylinder, 90 said main piston closing the open end of said hollow plunger as it approaches the upper end of the main cylinder, thereby trapping and compressing fluid in the said upper end of said main cylinder, said hollow plunger being raised from said piston to permit fluid to flow to the upper end of said main cylinder by said fluid exerting a force within the said hollow plunger between the upper end of the main piston and the lower end of the auxiliary piston when such fluid is admitted to the passage conveying said fluid to the upper end of said main cylinder.

3. In a hammer having a main cylinder provided with a main piston, passages for conveying fluid to and from the opposite ends of said main cylinder, and means for controlling the flow of fluid to and from said passages, the combination therewith of an auxiliary cylinder having an auxiliary piston provided with a hollow plunger extending into the upper end of said main cylinder and adapted to be engaged by said main piston as the same approaches the upper end of said main cylinder, said hollow plunger being open at its end toward said piston and having openings communicating with the fluid passage for the upper end of said main cylinder, said main piston closing the open end of said hollow plunger as it approaches the 110

upper end of the main cylinder, thereby trapping and compressing fluid in the said upper end of said main cylinder, means for conveying operating fluid from the lower end of said main cylinder to the upper end of said auxiliary cylinder to force said hollow plunger into said main cylinder when said operating fluid is admitted to the passage leading to the said lower end of said main cylinder to raise the main piston therein, said hollow plunger being raised from said piston to permit fluid to flow to the upper end of said main cylinder by said fluid exerting a force within the said hollow plunger between the upper end of the main piston and the lower end of the auxiliary piston when such fluid is admitted to the passage conveying said fluid to the upper end of said main cylinder, and the spent fluid is permitted to flow from the lower end of said main cylinder and from the upper end of said auxiliary cylinder, by the reverse operation of the means controlling the flow of said fluids to and from said fluid passages.
